UNITED STATES PATENT OFFICE.

MARTEN FANDERS, OF DILLER, NEBRASKA.

AUTOMATIC DOOR OR GATE.

Application filed April 20, 1923. Serial No. 633,491.

To all whom it may concern:

Be it known that I, MARTEN FANDERS, a citizen of the United States, residing at Diller, in the county of Jefferson and State 5 of Nebraska, have invented certain new and useful Improvements in Automatic Doors or Gates, of which the following is a specification.

My invention relates to automatic doors 10 or gates, and it is designed for the purpose of entirely eliminating the necessity of getting out of the automobile for either opening or closing the garage door.

In stormy weather particularly it becomes 15 highly desirable that the driver be able to enter the garage without wading through the mud to unlatch and to open the door. It is equally desirable when driving out of the garage in stormy weather that the door 20 be automatically closed and latched in closed position. Frequently it becomes necessary that a definite period of time elapse between the opening and the closing of the garage door, as when changing clothes in the garage 25 or when carrying packages from the garage to the house after a trip to the store.

I am aware that numerous attempts have 30 been made to design a device which would satisfactorily solve the numerous problems entering into a structure of this sort. Many of the prior devices depend on the use of pivoted tracks which are intended to set in motion the operating mechanism of the door 35 opener, but it is obvious that in very cold weather the accumulation of ice and frozen mud under the tracks will effectively prevent the operation of such devices at the very time when they are most needed.

In my device, provision is made for first 40 unlatching the garage door and then swinging the door through a definite limited arc, both actions resulting from the direct pressure of the moving automobile on the door. The automatic action which follows opens 45 the door to its full opening and latches it in its open position, and later after a definite, predetermined period of time it closes the door and latches it in its closed position.

Referring now to the drawings forming 50 part of my application, and in which like numerals refer to like parts in the description,

Figure 1 is a perspective view of the 55 upper portion of the garage door and of all the door operating mechanism, as viewed from below and slightly to one side thereof.

Figure 2 is a top plan view of a double door and of parts of the operating mechanism.

Figure 3 is a top plan view showing the 60 pivotal movement of the sinuous rod resulting from the movement of the actuating rod.

Figure 4 is a diagram showing the movement of the roller during the door closing 65 movements.

Figure 5 is a view in detail of the catch for holding the door in open position.

Figures 6 and 7 are views in detail of the 70 outer end of the actuating arm, and showing the swivelled connection of the roller therewith.

Figure 8 is a fragmentary view of the mechanism for resetting the timer.

Figures 9 and 10 are plan and edge views 75 respectively of the spring hinge which I prefer to use as a part of my door opening mechanism.

Figures 11 and 12 are side elevation and 80 plan view respectively of my timer.

Figure 13 is a side elevation of a portion 85 of the timer, and showing particularly the relation of the timer actuating rod with the timer.

Figure 14 is a view of a portion of the timer with part broken away to show the interior mechanism for setting the timer for any desired predetermined time.

Figure 15 is a perspective view of a portion 90 of the latch operating mechanism.

Figures 16 and 17 are edge views of the 95 garage door, and showing the latch operating mechanism in its two positions.

Figure 18 is a fragmentary view of the connection whereby the top and bottom latches are actuated simultaneously.

Figure 19 is an edge view of the bottom 100 part of the door, and showing the device for holding the bail shaped hanger out of the way of the automobile when the doors are open.

Figure 20 is a front view of the bottom portion of one of the doors, and showing a modification for use in connection with automobiles which are equipped with front 105 bumpers.

My invention contemplates the use of two springs or sets of springs, the one for opening the door and the other for closing it, the two being more or less in equilibrium. Mechanism is also provided for disturbing the equilibrium through the pressure of the 110

automobile against the door, whereby the door will be further opened through the action of one of the springs or sets of springs. The door is then held latched in its open position until released by the timing device which also releases the door closing spring.

My invention may be applied to either a single or a double door. I have shown it as applied to a double door, but it will be readily apparent that the main structural features will function in identically the same manner with a single door as with a double door.

15 In the drawings numerals 10 and 11 refer to the two parts of a double door, the part 10 being that portion which is operated directly by the springs. The doors are hinged to the door casing in the usual manner by 20 means of hinges, and preferably of the type of hinge shown in Figures 9 and 10, wherein a coil spring is under tension when the doors are in their closed position. A tension spring 12 is secured at one of its ends to the 25 door 10 and at its other end to the door casing or other convenient part of the garage. The spring 12 is on the outside of the door and exerts its tension to close the door when open and to hold it closed.

30 Inside the garage and adjacent the hinged edge of the door 10 I secure an L-shaped beam 13, preferably constructed by bending a suitable length of channel iron with the channel side of the channel iron on the in- 35 side of the angle. Each arm of the L-shaped beam 13 is provided with a vertical aperture passing through both walls of the channel iron, and through each of these apertures I pass a bushing (not shown) to serve as a 40 pivot bearing. The vertical portion of a right-angled rod 14 passes through the bushing of one of the apertures with the horizontal portion of the rod underneath the beam 13. The rod 15 is secured to the rod 45 14 at the angle and in alignment with the horizontal portion, thus becoming in effect a continuation of the horizontal portion of the rod 14. The free end of the rod 14 is provided with a roller 16, preferably with 50 roller bearings or other friction reducing devices. The roller 16 is adapted to travel in the track 17 which is secured in horizontal position to the upper portion of the door 10. During the opening movement of the door 55 10 the thrust of the roller 16 will be against the door itself, but in the closing movement of the door the roller 16 will bear against the inner wall of the track 17.

The sinuous rod 18 has three bends in its 60 horizontal plane, as shown in Figures 2 and 3, and its free end is slightly downturned and into horizontal position (Figure 4). The opposite end of the rod 18 is upturned and passed through the bushing of the sec- 65 ond of the vertical apertures in the beam 13.

The door opening spring 19 is secured at one of its ends to the door 10 adjacent the edge of the door opposite its hinge. The opposite end of the tension spring 19 is secured to the free end of the sinuous rod 18. 70

It is evident that if the door 10 is partially opened in any manner, the roller 16 will travel in its track 17 causing the actuating rod 15 to swing on its pivot. The free end of the actuating rod thus swings into 75 contact with the sinuous rod 18, the main portion of which lies in the plane of movement of the actuating rod 15. In order to reduce friction between the sinuous rod 18 and the free end of the actuating rod, and 80 to properly hold the two rods in contact with each other during their relative movements, I have provided a swivelled collar 20 for the free end of the actuating rod 15. The rocking movement of the collar 20 on 85 the rod 15 is limited to one quadrant. The collar 20 has a projecting guard 21 spaced therefrom, and between the collar 20 and guard 21 is journalled a wheel 22. The wheel 22 has a concave periphery 90 whereby the wheel is adapted to seat against the rod without danger of lateral displacement during the movements. The partial opening of the door thus causes the wheel 22 to bear against the sinuous rod 18 and to 95 swing that rod on its pivot, for purposes to be explained later in the description.

Secured to the upper projecting end of the sinuous rod 18 and mounted to swing with the sinuous rod is a bent rod having 100 two arms 23 and 24. The arm 23 has a hook shaped extremity which is adapted to cooperate with the catch 25 secured to the door 10. The catch 25 is mounted on a vertical pivot and is provided with a compression 105 spring 26 for permitting the engagement of the catch 25 with the hooked end of the arm 23 when the door is in its open position. A spring 27 connects the free end of the arm 24 to the front wall of the garage. The spring 27 is always under tension in all of 110 its positions, but the tension is manifestly greatest when the door is closed, as in the position shown in Figure 2. The tension of the spring 27 is thus mainly exerted toward 115 swinging the arm 24 into alignment with itself. The swinging of the arm 24 is however accompanied by the swinging of the sinuous rod 18. The spring 27 thus assists in opening the door 10. 120

The mechanism for releasing the holding devices and permitting the door to close after a definite predetermined period of time is shown at the right in Figure 1 and in detail in Figures 11, 12, 13, and 14. A strap 28 is securely bolted to the door casing. The strap is bent to provide an upper horizontally extending arm with its side in a vertical plane. A rod 29 is also secured to the door casing. The rod 29 has a lower horizontal 125 130

portion and an outer vertical portion, the upper extremity of the vertical portion passing through a loop in the outer extremity of the strap 28. The free extremity of the sinuous rod 18 rides in its movements over the upper edge of the horizontal portion of the strap 28. The projecting extremity 30 of the rod 29 serves as a seat and as a stop for the outward movement of the free extremity of the sinuous rod. A lever 31 is pivoted to rock on the strap 28. The rocking movement is however limited by a pin and slot connection 32 at the inner end of the lever. A rigid arm 33 is connected through a tension spring 15 with the strap 28 in such a way that the lever 31 will extend into the path of the sinuous rod to permit that rod to pass over the lever in the opening movement of the door but holding the sinuous rod against retrograde movement during the time while the door is open.

The arm 35 is secured at one of its ends to the door casing and projects horizontally between the horizontal portions of the strap 28 and the rod 29. To the arm 35 at its outer extremity is pivoted the tripping mechanism, which consists mainly of a frame 36 carrying two receptacles 37 and 38. It should here be noted that the pivotal point 39 is not midway between the two receptacles but is placed off center to afford greater leverage to the receptacle 38 than to the receptacle 37. The interiors of the two receptacles are connected by an upper or air conduit 40 and a lower or liquid conduit 41. As the frame is tilted in one direction or the other, the liquid will obviously flow from the higher to the lower of the two receptacles. In order to control the rate of flow of the liquid I provide an adjustable needle valve 42 in the receptacle 37 for the liquid conduit 41. My preferred construction is shown in Figure 14, where the needle valve 42 is secured to the end of a U-shaped leaf spring 43, which is made adjustable by means of a thumb nut 44. The frame 36 is also provided with two pins 45 and 46, which may if desired be surrounded by rollers to reduce friction. The pin 45 cooperates with the curved leaf spring 47 to yieldably hold the frame 36 in certain positions, and the pin 46 cooperates with the lower hooked end of the rod 48 to trip the lever 31. Both of these relations will be more fully described in connection with the operation of the entire mechanism. The receptacle 37 is provided with a laterally projecting button 49 which is adapted to retain the looped lower end of the rod 50, as shown in Figure 13. Referring now to Figures 1 and 8, it will be seen that the upper end of the rod 50 is pivoted to a bell crank lever 51 which in turn is pivoted to a support on the beam 13. The extremity of the other arm of the bell lever 51 is connected through a link 52 with a later-

ally projecting arm 53 on the vertical portion of the right angled rod 14. During this lifting movement the button 49 will rest in the bottom of the loop, but a further elevation of the receptacle 37 can take place within the limits permitted by the length of the loop and independently of the movement of the link 52.

The mechanism thus far described is that which causes the door 10 to open and close. It is desirable however that the doors 10 and 11 be actuated simultaneously or substantially so, and for this purpose I have added the following features to the mechanism already described. A crank arm 54 is secured to the upper projecting end of the right angled rod 14 and in such a way that the movements of the rod 14 are imparted to the crank arm 54. One end of a link 55 is pivotally connected to the free end of the crank arm 54, the opposite end of the link 55 being pivoted to the door 11 as shown in Figure 2. The connection 57 is heavily braced to withstand the strains to which it is subjected during the opening and the closing of the door.

My garage doors are provided with latches and with means for automatically latching and unlatching the doors. These devices are shown in plan and in their relation to the double doors in Figure 2, and the details of the devices are shown in Figures 15 to 20 inclusive. Each door is provided with top and bottom latches 58 and 59 respectively. A suitable bail shaped hanger 60 is pivoted at a suitable height inside the door with only the horizontal portion and one of the arms on the outside. The actuating arm 60^a of the hanger 60 is entirely on the inside of the door. A roller 61 surrounds the horizontal portion of the hanger 60. The pressure of the automobile wheel, as shown in Figure 17, will cause the hanger to rock on its pivots. In order to prevent injury to the door and to the hanger, I secure a buffer 62 of any suitable material to the door in the path of the swinging hanger.

The arm 60^a of the hanger terminates above its pivot in a flattened projection 60^b, which projection is provided with a series of apertures. A chain or cable 63 is connected at one of its ends to the bottom latch 59 and at its other end to the projection 60^b through one of the apertures. The top latch 58 has secured thereto a similar chain 64, the bottom end of which is secured to the end of a pivoted lever 65, as shown in Figure 18. A rod 66 connects the outer end of the lever 65 with the end of the projection 60^b. It is obvious that when the roller 61 is pressed inwardly the chains 63 and 64 will both be subjected to tension to thereby unlatch the latches. It is obvious however that the unlatching mechanism will function in identically the same manner with either a top or bottom latch.

alone as with the combination of the two latches, and I reserve to myself the right to omit either the top or the bottom latch from my combination.

5 I also add various incidental features of considerable importance to the latching and unlatching mechanism. The hook 67 is suspended from the door, and when it is desired to lock the latches it is only necessary to pass the hooked end of the hook 67 through one of the apertures of the projection 60^b, as shown in Figure 16. When the door is open, the bail shaped hanger 60 is apt to be injured or torn off by the 10 automobile, and in order to hold the hanger 60 out of the way of the automobile, I provide a pivoted lever 68, as shown in Figure 19. During the opening of the door the lower end of the lever 68 comes in contact with the stake 69 and the upper or looped end of the lever pushes the hanger 60 with its roller 61 against the door and out of the way of automobiles moving through the door. The weight of the roller 15 61 is such that in some cases it is liable to destroy the equilibrium of the hanger 60 and to accidentally unlatch the door. To avoid this difficulty I have added a spring 70 of just sufficient tension and so positioned as to counterbalance the weight of the roller. Still another of these incidental features is shown in Figure 20. Automobiles equipped with front bumpers will not properly engage the roller 61, and in such 20 instances I have found it necessary to substitute a plate 61' for the roller 61.

In the operation of my automatic door operating mechanism, the automobile is caused to slowly approach the closed door. 40 The pressure of the automobile against the hanger 60 swings the hanger on its pivots and releases the latches 58 and 59, whereupon the door will begin to open under the continued pressure of the automobile. 45 The initial opening movement of the door, through an arc of about forty-five degrees, is thus brought about directly by the pressure of the automobile against the door. During this initial movement of the door, 50 certain important movements take place in the operating mechanism. At first the spring hinges exert their tension in a direction tending to open the door, but the tension of the hinge springs is opposed by the 55 greater tension of the spring 12. The movement of the door under the forward pressure of the automobile causes the roller 16 to travel in the track 17. The travel of the roller 16 results in an arcuate movement of the rod 14 about its pivot, and also of the rod 15 which is connected to the rod 14. The arcuate movement of the rod 15 almost immediately brings the end 60 of the rod with its roller 22 into contact 65 with the sinuous rod 18. The pressure of

the roller 22 against the rod 18 results in an arcuate movement of that rod about its pivot, the free end of the rod 18 traveling on the track 28 and carrying with it the outer end of the door opening spring 19, 70 whereby the spring 19 becomes stretched. Referring now to Figure 3, the roller 22 will make its first contact with the rod 18 somewhere on the first curve which is designated *a* in that figure. The movement of 75 the roller 22 will be toward the right as viewed in Figure 3, and the arcuate movement of the rod 18 will be very rapid as the roller 22 moves from point *a* to point *b*. When the roller has reached point *b*, the 80 free end of the rod 18 has reached its extreme position, as shown in dotted lines, and is latched between the abutment 30 and the latch 31. At this point the door opening spring 19, while at its maximum tension, 85 is not sufficiently off center to overcome the tension of the spring 12. Slight further movement of the roller 22 beyond the point *b* suddenly changes the angles of both springs with respect to each other and to the door, throwing the door closing spring 90 into a position nearer dead center than before, and at the same time throwing the door opening spring into a position where its full tension immediately becomes effective. Simultaneously with this action, the 95 roller 22 rides out of contact with the rod 18. This is because the roller is forced to travel in a horizontal plane while the rod 18 curves downwardly at or near the point *b*, as shown in Figure 4. The difference 100 in effective tension between the two springs during the initial door opening movement of the door is greatest just after the roller 22 has left point *b* on the rod 18. The door 10 is thus opened to its full opening, 105 moving the horizontal portions of rods 14 and 15 into substantial parallelism with itself. During the arcuate movement of the rod 14, the crank arm 54 is moved through 110 a similar arc. It should be remembered that the initial action of the automobile is positive on both doors 10 and 11, but by the time that the action of the spring 19 has been brought into play, the angle 115 between the door 11 and the link 55 has been so increased that the thrust of the link on the door is positive and effective so that the pressure of the link will readily open the door the remaining distance without strain 120 on the door or linkage. 125

The action of the door in its opening movements is accompanied by certain movements in the timing mechanism. Figures 1 and 11 show the timing mechanism in its position when the door is in its closed posi- 130

tion. The arcuate movement of the rod and pivot 14 results in a lowering of the pivotal point of the bell crank 51 and the link 52. By referring to Figure 8, it will be seen that this movement results in the lifting of the rod or link 50 and of the receptacle 37 which is secured to the lower end of the link 50. This lifting simply places the two receptacles more or less on a level with each other, with the button 49 resting in the bottom of the loop in the lower end of the link 50. In other words, the linkage does not lift the receptacle 37 to its full height, but the loop permits other forces to act to lift 15 that receptacle to its full height.

While I may use any liquid in my timer, I prefer to use a liquid having a low freezing point, considerable weight, and low viscosity. The oils used in the crank case of the automobile are well suited for this purpose, but I do not desire to be restricted to their use. Just before the lifting of the receptacle 37 as above described, all of the liquid is in receptacle 37, but when the two are shifted 25 to a substantial level, the liquid begins to flow through the conduit 41 into the receptacle 38. It is assumed that the needle valve has been previously adjusted to control the rate of flow of the liquid to the owner's 30 convenience. When sufficient liquid has passed from the receptacle 37 to receptacle 38 to throw the preponderance of weight on the side of the receptacle 38, there is a tendency for the receptacle 38 to fall within the limits 35 of the loop in the link 50. The leaf spring 47 however acts as a brake, and this braking action combined with the eccentrically positioned pivot 39 causes the receptacle 38 to fall suddenly instead of slowly. In the 40 falling, the pin 46 is caught in the hooked end of the link 48, the sudden tension on the link 48 causing the unlatching of the latch 31. This releases the end of the sinuous rod 18 which is immediately carried back to its 45 original position by the spring 19. The pivotal movement of the rod 18 moves the hook 23 out of engagement with the latch element 25, so that the door is no longer held latched in open position. After the above described 50 movements which result in the relaxing of the spring 19, the greater tension is in the spring 12, which immediately closes the door 10. The door 11 is closed at the same time through the action of the link 55, 55 and the latches 58 and 59 of both doors enter their sockets to hold the doors closed against accidental opening. In opening the doors for the purpose of driving the automobile out of the garage, the initial opening movement is done manually but the subsequent automatic movements are identical with those above described. In driving the automobile out of the garage, the timer 60 gives the driver ample time to leave the garage before the doors close, and the mech-

anism insures the closing and latching of the doors without personal attention on the part of the driver or someone else.

My invention will be found useful in any place where automobiles are stored. In public garages and repair shops, the driver enters without calling on one of the mechanics to open the door and without stopping the car in order to open the door himself. The farmer whose garage is equipped with my 70 door opener can drive into the garage in all kinds of weather, and he can have his timer set to give him ample time to remove all of the parcels from the garage before the door closes automatically, and when he drives the 75 automobile out of the garage he has the assurance that the door will close and latch itself to keep out the wind, rain, and live stock. My automatic door operator will be 80 equally useful in the private city garage. 85 This is especially true of the garage which is built into the dwelling. The driver is not put to the necessity of getting out of the automobile except under shelter. The usefulness of the automatic opener is not limited 90 however to garage doors. It is obvious that the advantages of my invention when used with a garage door would also be present in a farm or other gate equipped with my attachment. 95

I have described my invention in very explicit terms and in great detail, but I do not wish to be restricted in all respects to the exact details which I have described, but I reserve to myself all of my rights to any or 100 all equivalents of the structures which I have shown and described.

Having thus described my invention in terms which will be readily understood by others skilled in the art to which it pertains, what I believe to be new and desire to secure by Letters Patent of the United States is:

1. In combination with a swinging garage door having a latch for holding the door latched in closed position, a spring secured to the outside of the door and to the garage and normally exerting its tension in a door closing direction, a second spring secured to the door and to means for tensioning it to open the door, and means whereby the pressure of the automobile on the outside of the door first unlatches said latch and then actuates said tensioning means to cause said second spring to open the door. 110 115

2. In combination with a swinging garage door, a spring secured to the outside of the door and to the garage and normally exerting its tension in a door closing direction, a second spring secured to said door and to means for tensioning it to open the door, means whereby pressure on the outside of the door will actuate said tensioning means to cause said second spring to open the door, and means for releasing the tension of said second spring at the end of a definite pre- 120 125 130

determined period of time whereby said first spring will exert its full tension to close the door.

3. In combination with a swinging garage door, a lever pivoted at one of its ends to a portion of the garage on the inside thereof, a tension spring secured to the inner side of the door and to the free end of said lever, a second lever pivoted intermediate its ends to a portion of the garage on the inside thereof, said second named lever having its ends bearing respectively said first named lever and the door, the arrangement being such that the partial opening of the door causes a pivotal movement of said second named lever which in turn causes the outward swinging of the free end of said first named lever to tension said spring and to thus complete the opening movement of the door.

4. In combination with a swinging garage door, a frame secured to the inner side of the garage and adjacent the hinged edge of the door, a lever pivoted to said frame and movable in a horizontal plane, a tension spring secured to the inner side of the door and to the end of said lever, a second lever pivoted to said frame and so positioned as to be actuated by the initial opening movement of the door and to transmit the movement to said first lever to tension said spring and to thus complete the opening movement of the door, and a latch mechanism associated with the door and with said first lever for holding the door latched in its open position.

5. In combination with a double garage door of the swinging type, a door opening spring inside the garage and having one of its ends secured to one of the door members and its other end secured to the garage, a lever for tensioning said spring, said lever being actuated by the initial opening movement of the door, means associated with said lever for causing the other member of the pair of door members to open in unison with the first member, a pivoted hook connected to and movable by said lever, a tension spring secured to the garage and to said pivoted hook, said last named spring being positioned to cooperate with the first named spring in causing the opening movement of the door, and a latch on the door for engaging said pivoted hook to hold the door latched in its open position.

6. In combination with a swinging garage door, a frame secured to the inner side of the garage and adjacent the hinged edge of the door, a lever pivoted to said frame and movable in a horizontal plane, a tension spring secured to the inner side of the door and to the end of said lever, an arm of shorter radius projecting in a parallel horizontal plane from said lever at its pivotal point, a tension spring secured to the free end of said arm and to a fixed portion of

the garage, and means whereby the initial opening movement of the door will cause the pivotal movement of said lever and arm to vary the tension in both of said springs to permit the springs under their combined tension to complete the opening movement of the door.

7. In combination with a swinging door for a garage or like building, a frame secured to the inner side of the building and adjacent the hinged edge of the door, a lever pivoted to said frame and movable in a horizontal plane, a tension spring secured at its ends to the end of said pivoted lever and to the inner side of the door respectively, and a second lever pivoted intermediate its ends to said frame, one end of said second lever being adapted to bear against said first named lever whereby the pivotal movement of said second lever will be transmitted to said first named lever to tension said spring, the other end of said second lever abutting against the inner side of the door, and means on the door for guiding the movements of said second lever.

8. In combination with a swinging door and door frame, a frame adjacent the door hinge and projecting in a horizontal plane and perpendicularly from the door frame, a lever pivoted at one of its ends to said projecting frame, a tension spring connecting the free end of said lever with the door, said lever having a curved portion, a second lever pivoted intermediate its ends to said projecting frame, said second lever having its ends abutting against the door and against the curved portion of said first named lever respectively, means secured to the door for holding the end of said second lever in contact with the door but permitting sliding movement therebetween, and means for holding the opposite end of said second lever in sliding contact with said first named lever at its curved portion, the arrangement being such that the initial opening movement of the door causes the pivotal movement of said second lever which in turn causes the pivotal movement of said first named lever through a greater arc to thereby subject said tension spring to increased tension to permit it to complete the opening movement of the door.

9. In combination with a swinging door and a door frame, a frame projecting from the door frame and in a horizontal plane, a lever pivoted at one of its ends to said projecting frame, a tension spring connecting the free end of said lever with the door, said lever having a curved portion, a second lever pivoted intermediate its ends to said projecting frame, said second lever having its ends abutting against the door and against the curved portion of said first named lever, said second lever having rollers at each of its ends, a horizontal guideway on the door

for one of the rollers, and a flange secured to said second lever and overhanging the roller which is in contact with the side of said first named lever.

5 10. In combination with a swinging door and a door frame, a frame projecting from the door frame and in a horizontal plane, a lever pivotally secured to said projecting frame, a tension spring secured at its ends 70
10 to the door and to the end of said lever respectively, means whereby a partial opening of the door causes said lever to swing on its pivot and to thus tension the spring, a track for guiding the movement of the 75
15 free end of said lever, and a latch on said track for holding said lever in its advanced position.

11. In combination with a swinging door and a door frame, a frame projecting from the door frame and in a horizontal direction, a lever pivotally secured to said projecting frame to swing in a horizontal plane, a tension spring secured at its ends to the door and to the end of said lever respectively, 80
20 means whereby a partial opening of the door causes said lever to swing on its pivot and to thus tension said spring, a track for guiding the movement of the free end of the lever, a latch on said track for holding said 85
25 lever in its advanced position, and a swinging latch operable by and secured to said lever, said last named latch being adapted to engage the door when in its open position.

12. In combination with a swinging door, 30 a door opening tension spring secured at one of its ends to the door, the opposite end of said spring being secured to a pivoted lever, means whereby the initial opening movement of the door causes the swinging 90
35 of said lever and the tensioning of said spring, a track for guiding the movement of the free end of said lever, a latch in said track for holding said lever in its advanced position, and automatic means for releasing 95
40 said latch.

13. In combination with a swinging door, a pivoted lever adapted to swing in a horizontal plane, a door opening spring secured to the door and to said lever, means whereby the initial opening movement of the door causes the swinging of said lever and the tensioning of said spring, a track for guiding the movement of the free end of said lever, a latch in said track for holding said 100
50 lever in its advanced position, a swinging latch secured to and actuated by said lever for holding the door when the door is in its open position, and automatic means for releasing said first latch whereby the tension of said spring will return said lever to its inoperative position and whereby said lever in its return movement will release said swinging latch from engagement with the door.

65 14. In combination with a swinging door,

a lever pivoted to swing in a horizontal plane, a tension spring secured at its ends to the door and to a swinging end of said lever, means whereby the initial opening movement of the door causes the swinging of said lever and the tensioning of said spring, a track for guiding the movement of the free end of said lever, a latch in said track for holding said lever in its advanced position, and a trip for releasing said latch at the end of a definite predetermined period of time.

15. In combination with a swinging door, a lever pivoted to swing in a horizontal plane, a tension spring secured at its ends to the door and to a swinging end of said lever, means whereby the initial opening movement of the door causes the swinging of said lever and the tensioning of said spring, a latch for holding said lever in its advanced position, a weight adapted to release said latch adjustable time controlled means for releasing said weight, and means for automatically restoring said weight to its initial position after the latch has been released. 90

16. In combination with a swinging door, a lever pivoted to swing in a horizontal plane, a second lever pivoted to swing in the same plane as said first lever, said second lever being adapted to communicate the initial opening movement of the door to said first lever, a spring secured to the door and to said first lever whereby the swinging of said first lever will tension the spring, a latch for holding said first lever in its advanced position, a weight adapted to release said latch, adjustable time controlled means for releasing said weight, and means actuated by said second lever in its return movement for restoring said weight to its initial position after the said latch has been released. 100

17. In combination with a swinging door, a lever, a tension spring secured to said lever and to the door, a second lever adapted to be actuated by the initial opening movement of the door and to actuate the first said lever to tension said spring, a latch for holding the first of said levers in its advanced position with the spring under maximum tension, means for releasing said latch to permit both of said levers to return to their initial positions, said latch releasing means comprising a weight for tripping said latch, and adjustable means for permitting the weight to drop at the end of a predetermined period of time, a crank arm on the pivot portion of said second lever, and a link connecting said crank arm to said weight to restore the weight to its initial position after said latch has been released. 110

18. In combination with a swinging door, two levers pivoted to swing in the same horizontal plane, a tension spring secured to the door and to one of the levers, the other of 115
120
125

said levers having its opposite ends abutting against the door and against said first lever whereby the initial opening movement of the door is transmitted through said second lever to swing said first lever and to thus tension the spring, a latch for holding said first lever in its advanced position, a weight for tripping said latch to permit both of said levers to return to their initial positions, adjustable time controlled mechanism for releasing said weight at the end of a predetermined

period of time, a brake for yieldably holding said weight in suspended position until released by the time controlled mechanism, a crank arm on the pivot portion of said second lever and actuated thereby, and a link connected with said weight and actuated by said crank arm to restore said weight to its initial position after the latch has been tripped. 15

In testimony whereof I affix my signature. 20
MARTEN FANDERS.
